ABSTRACT OF THE DISCLOSURE

High aromatic content motor fuel is produced from C₅—C₈⁺ naphtha by separating the naphtha into a C₅—C₆ cut, a separate C₇ cut and a C₈⁺ cut; catalytically dehydrocyclizing the C₇ cut; catalytically reforming the C₈⁺ cut; and thereafter combining the three fractions. In preferred modes of operation, the C₇ cut is also subjected to catalytic reformation and the C₅—C₆ cut is isomerized before combination with the other hydrocarbon fractions.

BACKGROUND OF THE INVENTION**Field of the invention**

This invention relates to an improved process for preparing high aromatic content hydrocarbon mixtures useful as motor fuels from C₅—C₈⁺ naphtha.

The prior art

Gasoline range naphthas comprise blends of 5 to 8+ carbon atom paraffins and are major constituents of gasoline. These naphthas have the disadvantage as motor fuels of having low octane numbers.

The formation of aromatic compounds from naphthas is known to increase the overall octane number. A great variety of processes involving catalytic reforming have been developed to increase the aromatic content of naphthas. In some of these reforming processes, such as the process disclosed in U.S. 2,918,422, issued Dec. 22, 1959 to Evering et al., the naphtha is separated into two fractions which are separately treated and then recombined.

STATEMENT OF THE INVENTION

It has now been found that the aromatic content of a C₅—C₈⁺ naphtha can be increased with improved efficiency when the naphtha is first fractionated into three fractions which are treated separately and thereafter blended. The three fractions and their separate treatments are (A) a C₇ fraction which is catalytically dehydrocyclized and then optionally catalytically reformed, (B) a heavy (C₈⁺) fraction which is catalytically reformed, and (C) a light (C₅—C₆) fraction which optionally is hydrogenated and isomerized. This process has the advantages over prior processes of permitting the C₇ fraction dehydrocyclization to be operated to maximize selectivity to aromatics without the usual risk of yield losses from C₅—C₆ cracking. Thus, both gasoline range hydrocarbon yield and aromatic selectivity can be optimized.

DETAILED DESCRIPTION OF THE INVENTION**The fractionation**

In accord with this invention a C₅—C₈⁺ naphtha is first separated into three fractions (cuts). This separation is suitably carried out in distillation columns as is known in the art to give a fraction consisting entirely or substantially (at least 90%, preferably at least 95%) of C₇ hydrocarbons, a heavy fraction containing primarily C₈⁺ hydrocarbons and a light fraction consisting essentially of C₅—C₆ hydrocarbons.

2

The C₇ fraction dehydrocyclization

The C₇ fraction is dehydrocyclized, that is, it is contacted with a catalyst which at elevated temperatures and in the presence of hydrogen causes paraffins having a chain of at least six carbon atoms to form into six carbon atom rings and thereafter causes these rings to dehydrogenate to aromatics. Very suitable catalysts for this reaction are nonacidic catalysts which contain on a nonacidic carrier at least one noble metal of Group VIII of the Periodic Table and at least one additional metal which has an electronegativity of from 1.6 to 2.0 and which belongs to the fifth or sixth periods of the Periodic Table. The Periodic Table referred to in this application is that found in the 43rd edition of the "Handbook of Chemistry and Physics" published by the Chemical Rubber Publishing Company.

The noble metals of Group VIII which may be present in the catalysts used for the C₇ fraction dehydrocyclization include platinum, palladium, rhodium, ruthenium, iridium and osmium. If desired, two or more of these metals may be present. Platinum is a preferred noble metal. The quantity of noble metal is suitably from about 0.01 to about five percent by weight, basis the entire catalyst, preferably from about 0.05 to about two percent by weight.

Metals found in the fifth and sixth periods which have electronegativities of from 1.6 to 2.0 and which are useful in these catalysts include silver, cadmium, mercury, indium, thallium, tin, lead, bismuth, molybdenum, tungsten, rhenium, and technetium. Electronegativity values for these metals are tabulated at page 78 of R. T. Sanderson's textbook "Inorganic Chemistry" (1967 edition, Reinhold). Preferred among these metals are tin and bismuth, with tin being most preferred. Combinations of these metals may be used. The amount of these metals added to the dehydrocyclization catalysts is suitably up to about five percent by weight, preferably from about 0.05 to about 2.5 percent by weight, basis the entire catalyst.

The support employed in these catalysts is preferably a porous nonacidic alumina often very suitably containing a small amount, for example, up to about one percent by weight, of sodium or potassium. These catalysts and their preparation are described in detail in U.K. patent application No. 39,408/69, filed Aug. 6, 1969.

The dehydrocyclization of the C₇ fraction is preferably carried out at a temperature of from about 375° C. to about 650° C., a pressure of from about 0.1 to about ten kg./cm.², a weight hourly space velocity of from about 0.1 to about 19, and a hydrogen to feed molar ratio of from about 0.5 to about five. Hydrogen should be added to stabilize the catalyst, but need not be pure. Hydrogen-containing reforming effluent gas may be used, for example.

The C₈ fraction reformation

The C₈⁺ fraction is subjected to catalytic reformation, that is, it is contacted with a catalyst which, at elevated temperatures and in the presence of hydrogen, causes the dehydrogenation of C₈⁺ alkylcyclohexanes to alkylaromatics, the dehydroisomerization of C₈⁺ alkylcyclopentanes to alkylaromatics and the isomerization of paraffins and aromatics.

Suitable catalysts for this purpose are acidic noble metal catalysts such as platinum on an acidic alumina carrier. Such catalysts may contain more than one noble metal and additionally may contain other metals, preferably transition metals, such as rhenium, tungsten, tin, bismuth and the like, and halogens such as chlorine or fluorine. Catalysts of this type are available commercially.

Catalytic reformation of the C₈⁺ fraction is suitably carried out at temperatures of from about 400 to about

600° C., preferably from about 450 to about 550° C., pressures of from about ten to about fifty kg./cm.², weight hourly space velocities of from about 0.5 to about ten, preferably from one to five, and a hydrogen to feed molar ratio of from five to fifteen.

It is often desirable to subject the C₇ fraction after dehydrocyclization to catalytic reformation in order to dehydroisomerize ethylcyclopentanes or dimethylcyclopentanes present in the C₇ fraction. These materials are effectively converted to aromatics by reformation. Dehydroisomerization of the dehydrocyclized C₇ fraction may be carried out separately by a separate reforming operation, as described above, or by combining the dehydrocyclized C₇ fraction with the C₈⁺ fraction prior to its reforming. It is preferred to reform the dehydrocyclized C₇ fraction by mixing it with the C₈⁺ fraction and together passing them over the same reforming catalyst.

The C₅–C₆ fraction hydrogenation and isomerization

Blending of the reformed C₈⁺ fraction and the dehydrocyclized and optionally reformed C₇ fraction with the previously separated C₅–C₆ fraction produces a useful high aromatic content motor fuel. An even higher octane product is achieved if the C₅–C₆ fraction is isomerized before it is blended with the other fractions. This treatment may be carried out by contacting the C₅–C₆ fraction with, for example, a hexafluoroantimony acid catalyst as described in British Pat. 981,311 or a platinum/mordenite catalyst as described in British Pat. 1,151,653. Treatment with a hexafluoroantimony acid catalyst is preferred.

If the C₅–C₆ fraction is to be isomerized, it is desirable to carry out two prior preparatory steps to ensure the life of the isomerization catalyst. The C₅–C₆ fraction typically contains benzene and most likely also contains sulfur compounds. Both benzene and sulfur compounds have adverse effects on the isomerization catalysts and should be removed. Benzene is most easily removed by hydrogenation using hydrogen and a Group VI or VIII catalyst such as an up to 65 percent by weight nickel on alumina or kieselguhr catalyst or a 0.1 to two percent by weight platinum on alumina catalyst.

Any sulfur present is typically present in the C₅–C₆ fraction primarily as mercaptans. These materials may be removed from the fraction by oxidative conversion to nonvolatile disulfides followed by distillation overhead of the C₅–C₆ fraction. This sulfur removal should be carried out prior to the benzene hydrogenation as the sulfur materials can harm the hydrogenation catalysts. The sulfur compound (mercaptan) oxidation may be simply effected by contacting the mercaptans with air or oxygen, preferably in the presence of a metal (especially copper) catalyst. Porous ion exchange resins containing from about five to about ten percent by weight of cupric copper are excellent mercaptan oxidation catalyst. This catalytic oxidation is carried out, in a preferred modification, prior to or during the initial naphtha fractionation. If a copper catalyst and oxygen (air) are both present in the distillation column used to separate overhead the C₅–C₆ fraction, any mercaptans present will be oxidized to disulfides and thus not taken overhead with the C₅–C₆ fraction, rather going into the C₇ or C₈⁺ fractions where they will have no adverse effect.

The blending

Following the above-described treatments, the C₅–C₆ fraction, the C₇ fraction, and the C₈⁺ fraction are blended together to give the final high aromatic content hydrocarbon motor fuel. It is not essential to the practice of this invention that these fractions be blended in exactly the proportions they were separated. Amounts of one or more of these fractions may be omitted from the final blend if desired. Generally, however, essentially all of each fraction is blended.

The following examples are provided to illustrate the process of this invention. They are not intended to be construed as limiting the scope of the invention.

EXAMPLE I

A C₅–C₈⁺ naphtha was split by distillation into a C₅–C₆ fraction, a C₇ fraction and a C₈⁺ fraction. The distillation column contained a commercial porous ion exchanger (Amberlyst 15) on which 7.8 percent weight copper in the form of cupric ions had been deposited. During the distillation a small amount of air was added to the feed in order to oxidize the mercaptans present in the naphtha feed to disulfides. The compositions of the C₇ and C₈⁺ fractions are given in Table I.

The C₇ fraction obtained was dehydrocyclized in a reactor I with the aid of a nonacidic catalyst which contained platinum and tin on alumina as carrier, and the product obtained was dehydroisomerized in a reactor II with the aid of a catalyst which contained platinum on acidic alumina as carrier. In three adiabatic reactors IIIA, IIIB and IIIC, which were connected in series, the C₈⁺ fraction was reformed with the aid of a catalyst which contained platinum on acidic alumina as carrier.

The products obtained from reactors II and III were combined. Table I gives the conditions in the reactors (pressures, temperatures, hydrogen/feed ratios, weight hourly space velocities), the yields of components which can be used as gasoline components, that is, the percentage of compounds with five or more carbon atoms, and the percentages of paraffins, naphthenes and aromatics therein (all percentages calculated on the quantity of feed), the content of aromatics in percentages of the total quantity of compounds with five or more carbon atoms, the ring retention and the selectivity.

TABLE I

	Reactor—			Composition of feed (C ₇ +C ₈ ⁺ fraction)
	I	II	III A,B, C	
Conditions:				
Weight hourly space velocity...	1	4	1.7	
Pressure, kg./cm. ²	3	10.5	28	
Hydrogen/hydrocarbon molar ratio.....	2	5	8	
Temperature, °C.....	500	462	1470	
Yield, percent weight:				
H ₂	2.6			
C ₁ –C ₄ paraffins.....	8.8			
Hydrocarbons with five or more carbon atoms (C ₅ ⁺)	88.6			100.0
C ₅ ⁺ paraffins.....	41.5			72.6
C ₅ ⁺ naphthenes.....	2.7			21.4
C ₅ ⁺ aromatics.....	44.4			6.0
Ring retention ¹	172			
Selectivity ²	72.4			
Aromatics in C ₅ ⁺ , percent weight.....	50.1			6.0

¹ Average temperature of 3 reactors.

² Percent weight of ring structures in product $\times 100$.

² Ring retention = percent weight of ring structures in feed

³ Selectivity = quantity of six-membered rings formed

³ Selectivity = quantity of converted paraffins plus cyclopentanes $\times 100$.

EXAMPLE II

The naphtha feed of Example I was fractionated in the manner of Example I. The C₇ fraction was dehydrocyclized as described in Example I. The product of this dehydrocyclization was passed together with the C₈⁺ fraction of the distillation into reactor IIIA of reactors IIIA, IIIB and IIIC in which the reforming was effected in the way described in Example I. The conditions in the reactors and the quantity and compositions of the product obtained from reactor IIIC are given in Table II.

TABLE II

Reactor	I	III	A, B, C
Conditions:			
Weight hourly space velocity	1	1.7	5
Pressure, kg./cm. ²	3	28	
Hydrogen/hydrocarbon molar ratio	2	8	
Temperature, °C.	500	1487	
Yield, percent weight:

C ₁ -C ₄ paraffins	18.4		
Hydrocarbons with five or more carbon atoms (C ₅ ⁺)	79.0		
C ₅ ⁺ paraffins	30.3		
C ₅ ⁺ naphthalenes	2.4		
C ₅ ⁺ aromatics	46.3		
Ring retention ²	178		
Selectivity ³	60.5		
Aromatics in C ₅ ⁺ , percent weight	58.5		

^{12,3} See footnotes bottom of Table I.

COMPARATIVE EXPERIMENT A

For comparison, the naphtha feed of Example I was freed from the C₅-C₆ fraction by distillation. The residue, which contained both the C₇ and the C₈⁺ fraction, was reformed in the three reactors, IIIA, IIIB and IIIC, which were connected in series. The reaction conditions, the yield and the composition of the product obtained are given in Table III.

TABLE III

Reactor	III	A, B, C
Conditions:		
Weight hourly space velocity	1.7	30
Pressure, kg./cm. ²	28	
Hydrogen/hydrocarbon molar ratio	8	
Temperature, °C.	1490	
Yield, percent weight:		
H ₂	1.6	
C ₁ -C ₄ paraffins	19.7	
Hydrocarbons with five or more carbon atoms (C ₅ ⁺)	78.7	
C ₅ ⁺ paraffins	36.8	
C ₅ ⁺ naphthalenes	2.4	
C ₅ ⁺ aromatics	39.5	
Ring retention ²	183	
Selectivity ³	54.3	
Aromatics in C ₅ ⁺ , percent weight	50.2	

^{12,3} See footnotes bottom of Table I.

Comparison of the results of Example I and the Comparative Experiment A shows that at almost equal contents of aromatics in C₅⁺, the yield obtained according to the process of the invention is considerably higher than that obtained according to the conventional process. Comparison of the results of Example II and the Comparative Experiment A shows that at almost equal yields a much higher content of aromatics in the product (which is an improvement of the quality) is attained with the process according to the invention.

We claim as our invention:

1. A process for converting a C₅ to C₈⁺ naphtha into a high aromatic content hydrocarbon motor fuel which comprises:

(a) separating the naphtha into a C₅ to C₆ fraction, a C₇ consisting of at least 90% C₇ hydrocarbons, and a C₈⁺ fraction;

- 6
 (b) subjecting the C₇ fraction to catalytic dehydrocyclization;
 (c) subjecting the C₈⁺ fraction to catalytic reformation; and

(d) admixing C₅ to C₆ fraction, dehydrocyclized C₇ fraction and reformed C₈⁺ fraction.

2. The process in accordance with claim 1 wherein the dehydrocyclized C₇ fraction is subjected to catalytic reformation prior to being admixed with the C₅ to C₆ fraction and the reformed C₈⁺ fraction.

3. The process in accordance with claim 1 wherein the C₅ to C₆ fraction is freed of any sulfur contaminants and subjected to hydrogenation and isomerization before it is admixed with the dehydrocyclized C₇ fraction and the reformed C₈⁺ fraction.

4. The process in accordance with claim 3 wherein the dehydrocyclized C₇ fraction is subjected to catalytic reformation prior to being admixed with the hydrogenated and isomerized C₅ to C₆ fraction and the reformed C₈⁺ fraction.

5. A process for converting a C₅ to C₈⁺ naphtha into a high aromatic content hydrocarbon motor fuel which comprises:

- (a) separating the naphtha into a C₅ to C₆ fraction, a C₇ fraction consisting of at least 90% C₇ hydrocarbons, and a C₈⁺ fraction;
 (b) subjecting the C₇ fraction to catalytic dehydrocyclization;
 (c) admixing the dehydrocyclized C₇ fraction with the C₈⁺ fraction and subjecting the admixture to catalytic reformation; and
 (d) admixing C₅ to C₆ fraction and reformed C₇ and C₈⁺ fractions.

6. The process in accordance with claim 5 wherein the C₅ to C₆ fraction is freed of any sulfur contaminants and subjected to hydrogenation and isomerization before it is admixed with the dehydrocyclized and reformed C₇ fraction and the reformed C₈⁺ fraction.
